3,134,244 LIQUID CHILLING DEVICES

Roy R. Hanson, 155 Cumberland Drive, Maryland Heights, Mo., assignor of one-fourth to William H. Anderson, Glencoe, Mo., one-fourth to Joseph H. Schierman, and one-fourth to George A. Blase, both of St. Louis, Mo.

Filed Jan. 15, 1962, Ser. No. 166,277

9 Claims. (Cl. 62—471)

This invention relates in general to certain new and useful improvements in refrigerating equipment and, more particularly, to liquid chilling devices.

It is the primary object of the present invention to provide a liquid cooling device or so-called "liquid chiller" which combines the various components of a refrigerating system into an efficient, compact and self-contained unit.

It is another object of the present invention to provide a liquid chilling device of the type stated which operates with a full-flooded evaporator, thereby eliminating the requirement for a surge tank.

It is an additional object of the present invention to provide a liquid chiller of the type stated which operates with a dry condenser.

It is also an object of the present invention to provide a liquid chiller of the type stated which has built-in refrigerant controls and requires no external control devices other than a thermostat.

It is a further object of the present invention to provide a liquid chiller of the type stated which has a low power requirement and, therefore, operates at low cost and at high efficiency.

It is still another object of the present invention to provide a liquid chiller of the type stated which is compact in size, sturdy in construction, and economical to manufacture.

In the accompanying drawings (three sheets)—

FIG. 1 is a side elevational view of a liquid chilling device constructed in accordance with and embodying the present invention;

FIG. 2 is a sectional view taken along line 2—2 of FIG. 1;

FIG. 3 is a sectional view taken along line 3—3 of FIG. 2;

FIGS. 4, 5, and 6, are fragmentary sectional views taken along lines 4—4, 5—5, and 6—6, respectively, of FIG. 2; and

FIG. 7 is a sectional view taken along line 7—7 of FIG. 2.

Referring now in more detail and by reference characters to the drawings, which illustrate a preferred embodiment of the present invention, A designates a liquid chiller comprising an outer cylindrical housing 1 having an integrally formed outwardly extending annular flange 2 extending around the periphery of its upper margin. An inwardly dished bottom plate 3 having a depending peripheral flange 4 is welded to the lower end of the housing 1. Mounted on, and supported by, the flange 2 is a conventional A.C. electric motor M having a cylindrical stator casing 5 which integrally includes a dish-shaped top wall 6. Integrally formed on and extending around the lower peripheral margin of the stator casing 5 is an outwardly extending flange 7 which is welded to the flange 2, thereby enclosing the motor M in an hermetically sealed internal chamber c.

Rigidly secured to, and extending around, the stator casing 5 is a circular cross-plate 8 having an axially upstanding peripheral flange 9, an annular series of uniformly spaced small ports p, and a large central aperture 10. The electric motor M includes a field winding 11 which is supported by the flange 9 within the stator casing 5. Disposed axially within the field winding 11 and

2

adapted for rotative movement is an armature 12 mounted on and keyed to a coaxially extending shaft 13 which is journaled in a self-aligning bearing 14 mounted in the top wall 6 of the stator casing 5. Disposed around the shaft 13 immediately beneath the bearing 14 is a rotary seal 15 which is biased toward the bearing 14 by a spring 16.

Mounted on, and carried by, the external end of the shaft 13, is a rotatable condenser housing 18 including an upper circular top wall 19 and an integrally formed depending cylindrical wall 20, the latter being provided with a plurality of circumferentially spaced elongated apertures 21 and outwardly projecting blades 22 which serve as air impellers. Mounted concentrically on the exterior of the stator casing 5, and held rigidly in spaced relation by a plurality of axial spacer-strips 23, is a spirally wound condenser tube 24. When the condenser housing 18 is rotated with the shaft 13, air will be drawn up through the open bottom into heat exchange relation with the condenser tube 24 and thereupon discharged through the apertures 21 by the blades 22.

Mounted on the underside of the cross-plate 8 by means of bolts 25 is a compressor 26 which includes a cylindrical compressor casing 27 and upper and lower spaced end-plates 28, 29, respectively. The end-plates 28, 29, are each annularly grooved to accommodate annular sealing rings 30, 31, preferably formed of neoprene rubber. The end-plates 28, 29, are also provided with outwardly extending bosses 32, 33, which are bored for accommodating bushings 34, 35, respectively.

At its lower end, the shaft 13 is journaled in, and extends through, the bushing 34, terminating in a diametrically enlarged portion 36, substantially as shown in FIG. 2. Connected to the lower end of the diametrically enlarged portion 36, within the compressor casing 27, is a diametrically offset or eccentrically located shaft 37, which is connected to a piston 38 forming part of the compressor 26, and connected to the lower end of the eccentrically located shaft 37 is a coaxially extending shaft 39 which is journaled in the bushing 35 and is provided with a diametrically enlarged head h. The operation and construction of the compressor 26 is more fully described in copending application Serial No. 102,060, filed April 10, 1961, and is, therefore, neither illustrated nor described in detail herein. A counterweight w is keyed to the shaft 39 in downwardly spaced relation to the compressor 26 to counteract the offset weight of the eccentrically located shaft 37. The compressor 26 is charged with a refrigerant such as Freon-12 or the like through a conventional fitting (not shown) and, in gaseous form, is drawn from the high side of the system into the compressor through a port 40 formed in the upper end-plate 28. The refrigerant is thereupon compressed and discharged from the compressor 26 under pressure into a high pressure gas manifold 41 mounted on the underside of the lower end-plate 29 and located concentrically around the shaft 39, substantially as shown in FIG. 2. The refrigerant gas under pressure passes into the manifold 41 through a check-valve 42 which consists of an arcuately shaped closure plate 43 normally lying in closurewise position over the port 40 and having outwardly extending flanges 44. The flanges 44 are bolted to and seated securely between two semi-circular clamps 45, 46, which are mounted on the boss 33. Thus, the compressor 26 will operate under the proper back-pressure and compressed refrigerant gas is discharged under high pressure into the gas manifold 41. Thereupon, the compressed refrigerant gas is conducted to the condenser tube 24 by means of a high-side gas line 47 which is connected to the upper portion of the condenser tube 24, substantially as shown in FIG. 2. As the air passes around the condenser tube 24 and out through the apertures 21, the refrigerant in the condenser tube 24

will be condensed to a liquid state and thereupon pass through a condenser discharge tube 48 into a capillary tube 49 spirally mounted on the inner surface of the housing 1.

Mounted on the upper surface of the bottom plate 3 within the housing 1 is an evaporator support plate 51. Disposed within the housing 1 and supported by the support plate 51 is a solid cylindrical disk 52 which is internally bored at both ends to provide an upper chamber 53 and lower chamber 54. The lower chamber 54, which is defined by the bored out disk 52 and support plate 51, serves as an evaporator 55 which is flooded with liquid refrigerant, and mounted therein is a heat exchange coil or worm 56 containing water or other liquid which is to be cooled. Connected to the heat exchange coil 56 and extending outwardly of the housing 1 through apertures 57, 58, formed within the bottom plate 3, are a fluid inlet line 59 and a fluid outlet line 60, respectively, the latter being provided with a conventional thermostat T which controls the electric current to the motor M. The disk 52 is further provided with a bore 61 providing communication between the capillary tube 49 and the evaporator 55, whereby the liquid refrigerant from the condenser coil 24 is delivered to the evaporator 55.

The upper chamber 53 is dished out at its lower portion to form a tapered bottom portion 62 which serves as an oil separator 63. A series of circumferentially spaced capillary passages 64 connects the chamber 54 with the chamber 53 and the oil separator 63. The disk 52 is further bored within the upper chamber 53 to provide an oil reservoir 65. An impeller blade 66 is disposed within the reservoir 65 and is provided with a shaft 67 which is threadedly connected to the lower end of the rotatable shaft 39. The impeller blade 66, shaft 67, and shaft 39 are internally bored to provide an oil supply line 68 for delivery of oil to the bushing 35. The eccentrically located shaft 37 and the lower portion of the shaft 13 are internally bored to provide a continuation of the oil supply line 68 for supplying lubricating oil to the compressor 26 and the bushing 34.

The operation of the liquid chilling compressor A is as follows. The electric motor M is energized, causing the armature 12 and the shaft 13 carried therewith to rotate. The rotation of the armature 12 will cause the eccentrically located shaft 37 to rotate and thereupon rotate the piston 38, operating the compressor 26 in the manner as described in the above-mentioned copending application. As the compressor 26 is operated, the gaseous refrigerant in the chamber c is drawn into the compressor 26 through the inlet port 40. When the gas refrigerant is compressed to the desired pressure, it is then expelled through the check-valve 42 into the gas manifold 41 where it is thereupon carried to the condenser tube 24 through the high-side gas line 47. The rotation of the armature 12 will, in turn, rotate the condenser casing 18 and cause air to be drawn upwardly into the area surrounding the condenser tube 24 and blown out through the air impellers. The rapidly moving air passing across the condenser tube 24 in heat exchange relation to the high-pressure refrigerant gas will thereupon condense the gaseous refrigerant into a liquid state. The liquid refrigerant is thereupon permitted to flow through the condenser discharge tube 48, the capillary tube 49, and thence into the chamber 54 forming part of the evaporator 55. A portion of the liquid refrigerant within the evaporator 55 will immediately vaporize upon expansion into the high-temperature, low-pressure area, and will pass through the evaporator tubes 64 into the hermetically sealed chamber c of the housing 1, as previously described. The oil which is carried by the gaseous refrigerant from the compressor 26 will also be carried upwardly through the evaporator tubes 64 and into the oil separator 63. As the oil is immiscible with the refrigerant at the low-temperature of the low-side, the oil will separate from the gaseous refrigerant and any liquid refrigerant carried

therewith in the oil separator 63. The oil will flow into the oil reservoir 65, whereupon the action of the impeller blade 66 will force the oil upwardly through the oil supply line 68 for lubricating the bushings 34, 35, and the compressor 26.

The load on the evaporator 55 is always determined by the amount of fluid to be cooled that is passed into the heat exchange coil 56. In this connection, it is to be noted that the evaporator 55 is a full-flooded evaporator. When the evaporator 55 begins to run cold, that is to say when the liquid being cooled by the evaporator 55 stays cold so that the load on the evaporator is accordingly reduced, the evaporator 55 may tend to return a small amount of liquid refrigerant entrained with the vaporized gas to the compressor 26, but such entrained liquid, if it exists in the return flow, will be prevented from entering the compressor intake port 40 by the large space of the upper chamber 53 and the circuitous path created by the ports p. When the load on the evaporator 55 is increased so that the evaporator 55 begins to run warm, the evaporator 55 will return a greater portion of gas into the compressor 26 and no entrained liquid refrigerant will tend to circulate.

It should be understood that changes and modifications in the form, construction, arrangement, and combination of the several parts of the liquid chilling devices may be made and substituted for those herein shown and described without departing from the nature and principle of my invention.

Having thus described my invention, what I claim and desire to secure by Letters Patent is:

1. A refrigeration system for use in liquid chilling devices and the like, said system comprising an outer housing internally subdivided into a low pressure gas chamber which is adapted to store gaseous refrigerant, an evaporator chamber and an upper chamber, an evaporator mounted within said housing and being located in said evaporator chamber, means within said housing providing communication between said evaporator and upper chamber, means within the housing for permitting the refrigerant to pass into the low pressure gas chamber after expansion in the evaporator, means for passing the liquid to be chilled through the evaporator, a compressor mounted within the housing above said evaporator and being located in said upper chamber, means operatively connecting said evaporator to said compressor, a condenser coil mounted externally of said housing and communicating with said compressor, means connecting said condenser coil to said evaporator, and an electric motor mounted within said housing for operating said compressor and being located in said low pressure gas chamber.

2. A refrigeration system for use in liquid chilling devices and the like, said system comprising an outer housing internally subdivided into a low pressure gas chamber which is adapted to store low pressure gaseous refrigerant, an evaporator chamber and an upper chamber located above the evaporator chamber and below the low pressure gas chamber, an evaporator mounted within said housing and being located in said evaporator chamber, means within said housing providing communication between said evaporator and upper chamber, means within the housing for permitting the refrigerant to pass into the low pressure gas chamber after expansion in the evaporator, means for passing the liquid to be chilled through the evaporator, a compressor mounted within the housing above said evaporator and being located in said upper chamber, means operatively connecting said evaporator to said compressor, a condenser coil mounted externally of said housing and communicating with said compressor, means connecting said condenser coil to said evaporator, a condenser casing rotatably mounted on said housing and concentrically encircling said condenser coil, said condenser casing having a plurality of heat-dissipating fins, said casing further having a plurality of air-intake apertures for permitting cooling air to pass around said coil

in heat-exchange relation, and an electric motor mounted within said housing for operating said compressor and being located in said low pressure gas chamber.

3. A refrigeration system for use in liquid chilling devices and the like, said system comprising an outer housing, a full-flooded evaporator mounted within said housing, means for passing the liquid to be chilled through the evaporator, a compressor mounted within the housing above said evaporator, an oil separator interposed between the evaporator and compressor and being adapted to separate the oil from the refrigerant leaving the evaporator, a reservoir for collecting the oil, pumping means provided in said reservoir for forcing the oil to the compressor, means operatively connecting said evaporator to said compressor, a condenser coil mounted externally of said housing and communicating with said compressor, means connecting said condenser coil to said evaporator, and motive means for operating said compressor and said pumping means.

4. A refrigeration system for use in liquid chilling devices and the like, said system comprising an outer housing, a full-flooded evaporator mounted within said housing, means for passing the liquid to be chilled through the evaporator, a compressor mounted within the housing above said evaporator, an oil separator interposed between the evaporator and compressor and being adapted to separate the oil from the refrigerant leaving the evaporator, a reservoir for collecting the oil, pumping means provided in said reservoir for forcing the oil to the compressor, means operatively connecting said evaporator to said compressor, a condenser coil mounted externally of said housing and communicating with said compressor, means connecting said condenser coil to said evaporator, a condenser casing rotatably mounted on said housing and concentrically encircling said condenser coil, said condenser casing having a plurality of heat-dissipating fins, said casing further having air-intake means for permitting cooling air to pass around said coil in heat-exchange relation, and an electric motor mounted within said housing for operating said compressor and said pumping means.

5. A refrigeration system for use in liquid chilling devices and the like, said system comprising an outer housing internally subdivided into a low pressure gas chamber which is adapted to store low pressure gaseous refrigerant, an evaporator chamber and an upper chamber located above the evaporator chamber and below the low pressure gas chamber, a full-flooded evaporator mounted within said housing, means for passing the liquid to be chilled through the evaporator, a compressor mounted within the housing above said evaporator and being located in said upper chamber, a gas manifold mounted in the discharge side of the compressor, a check-valve mounted on the discharge side of the compressor and being interposed between the compressor and manifold for imposing unidirectional flow from the compressor to the manifold, means operatively connecting said evaporator to said compressor, a condenser coil mounted externally of said housing and communicating with said compressor, means connecting said condenser coil to said evaporator, a condenser casing rotatably mounted on said housing and concentrically encircling said condenser coil, said condenser casing having a plurality of heat-dissipating fins, said casing further having a plurality of air-intake apertures for permitting cooling air to pass around said coil in heat-exchange relation, an electric motor mounted within said housing in vertically spaced relation to said compressor, and a vertically extending shaft driven by said motor and being adapted to operate said compressor and rotate said condenser casing.

6. A refrigeration system for use in liquid chilling devices and the like, said system comprising an outer housing internally subdivided into a low pressure gas chamber which is adapted to store gaseous refrigerant, an evaporator chamber and an upper chamber located between the evaporator chamber and the low pressure gas chamber,

a full-flooded evaporator mounted within said housing and being located in said evaporator chamber, means within said housing providing communication between said evaporator and upper chamber, means within the housing for permitting the refrigerant to pass into the low pressure gas chamber after expansion in the evaporator, means for passing the liquid to be chilled through the evaporator, a compressor mounted within the housing above said evaporator and being located in said upper chamber, an oil separator interposed between the evaporator and compressor and being adapted to separate the oil from the refrigerant leaving the evaporator, a reservoir for collecting the oil, pumping means provided in said reservoir for forcing the oil to the compressor, means operatively connecting said evaporator to said compressor, a condenser coil mounted externally of said housing and communicating with said compressor, a capillary tube connected at one end to said condenser coil and at the other end to the evaporator, a condenser casing rotatably mounted on said housing and concentrically encircling said condenser coil, said condenser casing having a plurality of heat-dissipating fins, said casing further having air-intake means for permitting cooling air to pass around said coil in heat-exchange relation, and an electric motor mounted within said housing for operating said compressor.

7. A refrigeration system for use in liquid chilling devices and the like, said system comprising an outer housing internally subdivided into a low pressure gas chamber which is adapted to store low pressure gaseous refrigerant, an evaporator chamber and an upper chamber located above the evaporator chamber and below the low pressure gas chamber, a full-flooded evaporator mounted within said housing, means for passing the liquid to be chilled through the evaporator, a compressor mounted within the housing above said evaporator and being located in said upper chamber, means operatively connecting said evaporator to said compressor, a condenser coil mounted externally of said housing and communicating with said compressor, means connecting said condenser coil to said evaporator, a condenser casing rotatably mounted on said housing and concentrically encircling said condenser coil, said condenser casing having a plurality of heat-dissipating fins, said casing further having air-intake means for permitting cooling air to pass around said coil in heat-exchange relation, and an electric motor mounted within said housing in vertically spaced relation to said compressor, and a vertically extending drive shaft driven by said motor, said drive shaft being operatively connected to a pump shaft eccentrically located with respect to said drive shaft, said pump shaft being operatively connected to said compressor.

8. A refrigeration system for use in liquid chilling devices and the like, said system comprising an outer housing internally subdivided into a low pressure gas chamber which is adapted to store gaseous refrigerant, an evaporator chamber and an upper chamber located between the evaporator chamber and the low pressure gas chamber, a full-flooded evaporator mounted within said housing, means within said housing providing communication between said evaporator and upper chamber, means within the housing for permitting the refrigerant to pass into the low pressure gas chamber after expansion in the evaporator, means for passing the liquid to be chilled through the evaporator, a compressor mounted within the housing above said evaporator, means operatively connecting said evaporator to said compressor, a condenser coil mounted externally of said housing, a gas manifold mounted on the discharge side of said compressor, a high-pressure gas line connecting said gas manifold to said condenser, a capillary tube connected at one end to said condenser coil and at the other end to the evaporator, an oil separator interposed between said evaporator and said compressor, a condenser casing rotatably mounted on said housing and concentrically encircling said condenser

coil, said condenser casing having a plurality of heat-dissipating fins, said casing further having air-intake means for permitting cooling air to pass around said coil in heat-exchange relation, an electric motor mounted within said housing in vertically spaced relation to said compressor and being located in said low pressure gas chamber, and a vertically extending drive shaft driven by said motor, said drive shaft being operatively connected to a pump shaft eccentrically located with respect to said drive shaft, said pump shaft being operatively connected to said compressor.

9. A refrigeration system for use in liquid chilling devices and the like, said system comprising an outer housing, a full-flooded evaporator mounted within said housing, means for passing the liquid to be chilled through the evaporator, a compressor mounted within the housing above said evaporator, means operatively connecting said evaporator to said compressor, a condenser coil mounted externally of said housing, a gas manifold mounted on the discharge side of said compressor, a high-pressure gas line connecting said gas manifold to said condenser, a check-valve interposed between said compressor and said manifold and being adapted to impose unidirectional flow from the compressor to the manifold, a capillary tube connected at one end to said condenser coil and at the

5
10
15

other end to the evaporator, an oil separator interposed between said evaporator and said compressor, a condenser casing rotatably mounted on said housing and concentrically encircling said condenser coil, said condenser casing having a plurality of heat-dissipating fins, said casing further having air-intake means for permitting cooling air to pass around said coil in heat-exchange relation, an electric motor mounted within said housing in vertically spaced relation to said compressor, and a vertically extending drive shaft driven by said motor, said drive shaft being operatively connected to a pump shaft eccentrically located with respect to said drive shaft, said pump shaft being operatively connected to said compressor.
